SYRINGE BARREL HAVING A HOODED NEEDLE

Stephen Saul Richman, Evanston, Ill., assignor to
Abbott Laboratories, North Chicago, Ill.

Filed Jan. 30, 1974, Ser. No. 438,068

Term of patent 14 years

Int. Cl. D24—04

U.S. Cl. D83—12 A

FIG. 1 is a perspective view of a syringe barrel having a hooded needle showing my new design;

FIG. 2 is a side elevational view;

FIG. 3 is a bottom plan view as viewed along the lines 3—3 of FIG. 2; and

FIG. 4 is a top plan view thereof as viewed along the lines 4—4 of FIG. 2.

I claim:

The ornamental design for a syringe barrel having a hooded needle, substantially as shown and described.
